UNITED STATES PATENT OFFICE.

CHARLES W. BROWN, OF MONTREAL, QUEBEC, CANADA, ASSIGNOR TO THE BELL TELEPHONE COMPANY OF CANADA, OF SAME PLACE.

TELEPHONE SYSTEM.

SPECIFICATION forming part of Letters Patent No. 393,612, dated November 27, 1888.

Application filed March 31, 1888. Serial No. 269,211. (No model.) Patented in Canada April 16, 1888, No. 28,932.

To all whom it may concern:

Be it known that I, CHARLES WARREN BROWN, of the city of Montreal, in the district of Montreal and Province of Quebec, Canada, have invented certain new and useful Improvements in Telephone Systems, (for which Letters Patent of Canada, No. 28,932, were granted to me on the 16th of April, 1888;) and I do hereby declare that the following is a full, clear, and exact description of the same.

The system to which my invention applies is that which has been adopted for large buildings to secure telephonic communication between the numerous departments therein. Such a system is shown and described in Patent No. 356,427, granted to C. E. Scribner, and which he calls a "Factory Telephone Exchange," but which can also be styled a "local" system. Such systems consist, essentially, of a separate instrument for each department, embracing a key-board and plug, a call-bell, transmitter, battery, and telephone, and the necessary connections. In addition to its adaptability to large buildings, such a system can also be used for local communication, such as between a main building or department and outbuildings in immediate vicinity, and also for village telephonic communication, if desired. In all such cases, however, for outside work or communication with another system a separate and distinct "general" telephone is required, and of course to this all parties in the building or community must come to hold communication with the exchange and outsiders.

The purpose of my invention is to do away with this general telephone altogether and give to each department or station in such local system separate connection with the exchange, in addition to their present power of speaking to any other department, and obviously allow exchange to call either of the departments. This object I attain by certain alterations in and additions to the mechanism for local communication above alluded to, which changes will now be briefly described.

I have separate instruments for each department, each of which includes, first, a key-board and plug, the same as before, except that an "exchange" key and push-button are added; second, a call-bell, the same as for-

merly, for signaling between the departments only; third, a transmitter differing from ordinary construction in so far that its battery has a complete circuit separate from the secondary circuit of the induction-coil; fourth, a telephone the same as formerly; fifth, a system of insulated springs operated by the telephone-lever to cut telephone in and out and to open and close the separate transmitter-battery circuit, also serving to keep closed the exchange-circuit, in which are arranged extension-bells to allow the exchange to call any particular department by special signal. In addition to these instruments I have a main or calling battery common to all of them, instead of an independent battery for each. Besides this the arrangement of the line connections and the foregoing mechanism is such as will enable one station, as formerly, to call another without calling other stations in the system, and also to allow any department to call the exchange without calling the other stations. Further, the arrangement renders possible a test as to whether the local circuit of each station is clear by each station without calling other stations, and provides means, in connection with the exchange-key, for calling the exchange, and a push-button whereby the exchange speaking-circuit is closed. For full comprehension, however, of the invention reference must be had to the annexed drawings, in which—

Figure 1 is a diagram of a system comprising three stations, two of which are shown in communication, the telephones being removed from their hooks or switch-levers, and the third in its normal position; Fig. 2, a sectional detail of the key-board, the section being taken so as to show the particular key for calling the exchange and the push-button for keeping the talking-circuit from same closed; and Fig. 3 is a detail of a pair of insulated springs on the exchange-line operated by the telephone-lever to keep same always closed, so that the extension-bells can be rung at any time.

Similar letters of reference indicate like parts.

As all the parts or mechanism of the system are well known to those skilled in the art to which this invention appertains, it is not considered necessary to illustrate them other-

wise than by diagram. It must also be understood that while the outfit of only three stations or departments is shown any number may be included in the system.

5 Referring to Fig. 1, I show in diagram in the stations Nos. 1, 2, and 3 the several parts or elements of an outfit, all of which, except the extension-bell, will of course be mounted on a board of the usual kind and arranged upon the wall. The extension bell will by preference be placed out of the way upon some convenient shelf.

A represents the key boards, each composed of four keys, a' a'' a^3 a^4 , of the kind shown in section in Fig. 2—viz., a metal base or stud with a central plug-hole and a projecting flat metal spring to be depressed, so as to make contact with the united terminals b' b'' b^3 b^4 of wires a' a'' a^3 from one pole of the main or calling battery X, which is common to all the stations and situated in any convenient part of the building.

a' a'' a^3 are the calling-keys of each station in the system, and a^4 is to call the exchange. 15 The connections between the keys of the several stations are made by wires $c'c''c^3$, as shown. An additional key, a^5 , for closing the exchange talking-circuit, is provided, and consists of a flat metal spring, a^6 , projecting from the opposite side of the stud of key a^4 and provided with a button or more convenient means—such as a hand cam-lever—acting on its free end for holding it depressed (while talking is going on) upon a terminal at end of a terminal wire, 20 b^6 , of the secondary circuit of the transmitter-coil, so as to leave one of the speaker's hands free in case he should want to write down a message. As these several keys are normally out of contact with the several terminals and 25 the circuit naturally broken, and as it is of course necessary that the exchange-circuit shall always be closed in order to ring the extension-bells at any time, I arrange a bridge, b^6 , over the spring of key a^5 , and by means of 30 this bridge and a screw set in same and bearing upon the spring a permanently-closed exchange-circuit is secured, as the exchange-line c^4 is carried into the station No. 1 and connected, first, with the stud of exchange-calling key a^4 , whence the circuit continues, 35 through spring a^6 , screw, and bridge b^6 , to a continuation of the exchange-line. This continuation leads from bridge b^6 of station No. 1 to exchange-calling key a^4 and bridge b^6 of station 40 No. 2, and so on through a further continuation of the line to the same parts in station No. 3, a closed circuit being maintained throughout all these parts. From the bridge in the last, 45 or No. 3, station the exchange-line is carried back to No. 1, where it is divided in two and terminates in two springs, d e , one on each side of the switch-arm of the telephone-hook H, but never coming in contact with it. Similar springs, d' e' , forming the terminals of the divided end of a continuation, c^6 , of the exchange-line, on which the extension-bell E of station

No. 1 is arranged, are furnished with knobs d^2 e^2 , of insulating material, which come in contact with the switch-arm, but of course have no electrical connection with it, and are acted upon by it to cause the respective pairs of springs d d' and e e' to make electrical contact. These springs are for the purpose of maintaining an unbroken exchange-circuit at this point whether the telephone be on the hook or off, and this is done when the telephone is on the hook by the switch-arm, as shown in No. 3 station, pressing spring e' into contact with spring e , and when the telephone is off, as shown in stations Nos. 1 or 2, by the contact of d and d' . This duplicate arrangement of springs is provided in each station, as shown, and it will be seen that the unbroken circuit passes through all the extension-bells E to ground.

Any station (say No. 3) can call the exchange without calling other stations by pressing key a^4 , which closes the break between exchange-line and main calling-battery X, and the current travels via the exchange-lines between the several stations and through the bridges b^6 , springs a^6 , and their studs in stations Nos. 2 and 1 to exchange.

F' F'' F^3 are the call-bells of each station, and P N the binding-posts of same, one, P, of which is connected by wire p to positive pole or earth-line of battery X, and the other by wire n to the telephone-hooks, which, when the telephone is hung on either of them, make electrical contact with either of the springs n' n'' n^3 , n^4 forming the terminal of calling-key wire c' , n^2 the same of branch c^{22} from calling-wire c^2 , and n^3 the same of branch c^{33} from calling-wire c^3 .

Suppose No. 3 desires to call No. 1, whose instrument we will presume is in its normal condition, the same as No. 3. No. 3 presses key 1, and the current travels along wire c' to spring n' , through telephone-hook, along wire n , to call-bell F' , and through same to earth by line p , this being done without calling No. 2 in any way; and, again, if No. 3 desires to test his call-bell to see if his own circuit is clear, he will press the key of his own station (marked 3) and make a battery-circuit from pole or terminal b^6 , up line c^6 , down its branch c^{33} , and back to key 3 by spring n^3 , telephone-hook, wire n , through call-bell F^3 , and by wire p to opposite pole of battery or earth-line. It will be seen that no other station is called during this operation.

All the parts of the instruments are normally in the position shown in No. 3 station, the telephone hanging on the hook and its switch-arm keeping the exchange-circuit closed by operating upon springs e e' , and the call-bell circuit in the same state by switch-arm bearing against spring n^3 .

T' T'' T^3 are the transmitters, of ordinary construction, save that I make its battery-circuit complete without becoming a part of the secondary circuit of the induction-coil.

t' t^3 represent the terminals of this complete

battery-circuit in the form of springs similar to those in the exchange-circuit and arranged on one side of the switch-arm, one, t' , being always out of contact with the arm, but the other, t^2 , insulated from it by a knob, of rubber or other material, being operated by it when the telephone is removed to close the break between them and so work the circuit.

5 S' S^2 S^3 represent the telephones with their terminals connected, respectively, to earth-lines and to one terminal, s , of the secondary coil of the transmitter, while a plug, z , is connected to the opposite transmitter terminal-wire, b^5 .

15 After calling any particular station by depressing the necessary key, the party calling inserts plug z in the plug-hole in the stud of that key, and as the party called also inserts his plug in the key bearing the number of his 20 own station telephonic communication is established, as shown, between stations Nos. 1 and 2, the telephone being of course off the hooks. The speaking circuit between these two stations is from ground terminal of and 25 through telephone S' , along terminal s of and through secondary coil of transmitter, along terminal b^5 , through plug z to key marked 1, whence it follows wire c' to key 1 in station No. 2 and takes a corresponding course from 30 this point through transmitter and telephone to ground.

What I claim is—

1. The combination, with a local telephone system in which each station can call and communicate directly with another independently of any special station or centralizing point to which the line of each station must converge, of a line-connection or closed circuit from an outside exchange entering each station, a signaling device (such as an extension-bell, E) in each station with which said line-connection is always in closed circuit except when either of the stations is in talking circuit with cen-

tral station, so that central can call any subscriber by special signal, a key in each station 45 to enable it to connect a calling-battery circuit with said line-connection or closed circuit, so as to call such outside exchange, and means—such as a key—in each station for connecting its telephone-circuit with the said line-connection or closed circuit, all as herein set forth.

2. In the individual station of a local telephone system, the combination of an individual local circuit-closing key or terminal of such station, a terminal of one pole of a main 55 battery-circuit, and a circuit confined to such station connecting such calling-key through spring-contact and telephone-hook with one terminal of an electro-magnet for operating call-bell, the other terminal of the magnet 60 leading to the other pole of said battery-circuit or to ground, all arranged and operating in the individual station, as herein described.

3. The combination, in a telephone system of a central-exchange office, of a local system in 65 which each station can call and communicate directly with another independently of any special station or centralizing point to which the line of each station must converge, and a line-connection or closed circuit from the exchange 70 entering each station in local system and composed of main line leading to first station in local system, extension-lines between each station connected at stations by devices adapted to open and close circuit, and further 75 extension-lines between each station and to ground carrying signaling devices, the pairs of springs d d' and e e' in each station of the local system connected with said further extension-lines, and means for securing contact of each 80 of said pairs, as and for the purpose described.

C. W. BROWN.
